Attorney.

UNITED STATES PATENT OFFICE.

WILLIAM VANDERMAN, OF WILLIMANTIC, CONNECTICUT.

WORK-BENCH.

SPECIFICATION forming part of Letters Patent No. 644,880, dated March 6, 1900.

Application filed June 17, 1897. Serial No. 641,129. (No model.)

To all whom it may concern:

Be it known that I, WILLIAM VANDERMAN, a citizen of the United States, and a resident of Willimantic, in the county of Windham 5 and State of Connecticut, have invented certain new and useful Improvements in Work-Benches, of which the following is a full, clear, and exact description, whereby any one skilled in the art can make and use the same.

10 The object of my invention is to provide a portable work-bench made of light and very strong material, capable of rough handling and extended use, and easily assembled.

To this end my invention consists of the 15 sectional work-bench, with its frame made of structural iron or steel, with the parts combined and arranged substantially as described and more particularly as recited in the within claims.

20 Referring to the drawings, Figure 1 is a view in side elevation of my improved work-bench with part cut away to show construction. Fig. 2 is a view in cross-section through the bench looking at the inner surface of one 25 of the end sections. Fig. 3 is a view, on an enlarged scale, of the preferred form of foot. Fig. 4 is an edge view of the parts of the bench in the knockdown form for packing.

In the accompanying drawings the letter *a* 30 denotes the end section of a bench, and this is made up of the legs *b* and *c*, which are of suitable angle-iron or rolled steel of L shape in cross-section. These legs are united at the upper ends by a cross-piece *d* of the same 35 material, firmly secured to the upper ends of the legs by the rivets 1, and located at points a suitable distance apart to afford support for a shelf removably secured in place, as by means of bolts, are cross-pieces *e*, of the same 40 material, also united to the legs by rivets 2. The web *d'* of the cross-piece *d* turns inward, as shown in Fig. 1 of the drawings, and through holes bored in this bolts 3 are passed, and by means of nuts on the threaded ends 45 of the bolts the planking forming the top *f* of the table is firmly united to the end sections.

Two such end sections as have been described are secured together by lengthwise 50 pieces *g* *g'* *h* *h'* of any desired length removably secured in place, as by means of bolts, and the end sections are secured against col-

lapsing by suitable cross-braces *i*, removably secured to the respective upper and lower ends of the opposing end sections, as shown in Fig. 1 55 of the drawings. This cross-bracing is not essential when two lines of shelves are used; but it is a desirable strengthening element of the construction. A similar cross-brace *k*, (shown in Fig. 2 of the drawings,) is secured 60 to the end, extending diagonally from the top of one leg to the bottom of the other leg. These cross-braces are preferably riveted or bolted to the horizontal pieces which support the shelves.

65 A shelf *l*, made of any number of planks or boards, fits within the framework formed by the horizontal connecting-pieces between the end sections and across the ends, the shelving being cut to a length which fits 70 snugly between the upturned webs of the angle-iron along the side and across the ends.

The side pieces, which connect the end sections, are simply bolted at opposite ends to the web or flange of the legs at opposite ends, 75 so that they may be removably secured in place, and in the same way the cross-braces are bolted, so as to be easily removed. By this construction of the parts the several sections of the bench may be packed into convenient form for transportation, as illustrated 80 in edge view in Fig. 4 of the drawings.

A foot *m* may be formed at the lower end of each upright leg by splitting the iron along its angle and turning out the material, or, if 85 preferred, the foot may be formed by a separate casting, such as is shown in top view in Fig. 3 of the drawings, and this is bolted or riveted onto the lower end of the leg.

An essential feature of my invention resides 90 in the angular shape of the parts of the bench forming the supports, each branch, in the case of the legs, forming means to which are secured different parts of the bench, and in other instances one branch of a part affords 95 the means by which said part is secured in place and the other branch affording a support for other portions of the bench. This construction of the supports of angular shape provides a maximum amount of strength with 100 a minimum weight of material, the different branches of an angular piece being comparatively thin, affording ready means for attachment of the pieces or for the support of an-

other piece; but I do not desire to limit myself to the exact form of the supports herein shown and described.

I claim as my invention—

- 5 1. In combination in a work-bench, end sections including legs and cross-pieces formed of angle-iron with the recesses in each instance facing inwardly, and a table secured to the outside of the horizontal branch of the top cross-piece.
- 10 2. In combination in a work-bench, end sections including legs and cross-pieces formed of angle-iron with the recesses in each instance facing inwardly, lengthwise pieces connecting the end sections and secured to the inside of one branch of the legs, and a table secured to the outside of the horizontal branch of the top cross-pieces.
- 15 3. In combination in a work-bench, end sections including legs and cross-pieces formed

of angle-iron with the recesses in each instance facing inwardly, a table secured to the outside of the horizontal branches of the top cross-pieces, and a shelf secured to cross-pieces with the ends of the shelf inclosed by the angle in 25 said cross-pieces.

4. In combination in a work-bench, end sections including cross-pieces formed of angle-iron with the recesses facing inwardly and legs formed of angle-iron with the recesses 30 facing inwardly, the ends of the legs being inclosed within the angle of the cross-pieces and secured to a branch thereof, and a table secured to the outside of the horizontal branch of the top cross-piece.

WILLIAM VANDERMAN.
